METHOD AND APPARATUS FOR
COMPLETING A WELLGordon A. Kessler, Pittsburgh, Pa., assignor to
The Texas Company, New York, N. Y., a cor-
poration of DelawareOriginal application April 28, 1945, Serial No.
590,763. Divided and this application October
1, 1948, Serial No. 52,332

5 Claims. (Cl. 166—1.)

1

This invention relates to the completion of a well with a gravel pack surrounding a screen or perforated liner, and more particularly to the placing of a screen or liner in a mass of gravel or other granular material previously deposited in the bottom of the well bore or in the wall cavity. The principal object of the invention is the provision of a method and an apparatus or an assembly of parts by means of which a well can be completed and placed on production with a minimum of time and effort.

This application is a division of application Serial No. 590,763, filed April 28, 1945.

In one method of gravel packing a well a screen or perforated liner is placed in the well cavity suspended from or attached to the lower end of a string of tubing and the gravel in a carrier fluid such as drilling mud is circulated downwardly through the annular space between the tubing and the casing. The carrier fluid passes into the screen or liner and then upwardly to the surface through the tubing string while the gravel is screened off and deposited in the space around the screen or liner. This is a very satisfactory method of graveling a well, but it naturally requires considerable equipment at the surface such as a device for mixing the gravel with the carrier fluid, a pump for forcing the mixture into the well and the carrier fluid upward again to the surface etc., and it also requires careful checking of the amount of gravel deposited.

Without any outstanding success, attempts have been made to force a screen or perforated liner downwardly into a previously deposited mass of gravel. Even when the screen portion is provided with a pointed or tapered lower end it is very difficult, if not impossible, to force the screen into and through the gravel mass to any appreciable distance since the gravel is not compressible and must be forced laterally into the side walls of the cavity or hole.

In accordance with the present invention a procedure is employed whereby an amount of gravel substantially equal in volume to the space to be occupied by the screen is removed from a previously placed gravel bed. Thus, the invention may be defined broadly as a method of completing a well with a gravel pack and screen, comprising filling a well cavity with gravel, forming a hole in the bed of gravel shaped to receive a screen by removing the gravel therefrom while maintaining the shape of the hole, and providing the shaped hole with a screen.

For a better understanding of the invention

2

reference may be had to the accompanying drawings in which:

Figure 1 is a vertical, sectional elevation through the lower portion of a well bore showing a screen in position surrounded by gravel pack;

Figure 2 is a similar view showing a modification;

Figure 3 is a similar view showing another modification;

Figure 4 is a sectional detailed view showing another manner of attaching the screen and inner tube to the drill pipe or tubing string; and

Figure 5 is another sectional detailed view showing the lower end of the screen of Figure 3 in a slightly different form.

Referring to the drawing a well bore 10 is shown as penetrating the formations 12 and being provided at its bottom with a cavity 14 within a producing formation 16. The hole 10 is also provided with a casing 18 cemented in place as indicated at 20 and a mass or bed of gravel or other granular material 22 is shown as having been deposited within the cavity 14. A pipe string 24 which may be drill pipe or tubing 25 has attached to its lower end a screen member or perforated liner 26 and the screen 26 has attached to its lower end a pointed section 28. Attached as by welding to the outer surface of the screen 26 and point 28 is a helical flange 30 extending throughout the length of the screen.

In placing the screen as shown in Figure 1 the cavity 14 is first filled with the gravel as by pouring the latter into the well bore at the surface, after which the screen 26 is lowered

35 suspended from the pipe string 24 until the point 28 reaches the level of the gravel bed 22. The pipe string is then rotated while being lowered slowly into the gravel bed and as the screen advances the flange 30 displaces gravel upwardly

40 into the annular space between the casing 18 and the lower portion of the pipe 24. Thus a hole is bored in the gravel bed and is maintained by the outer surface of the screen 26. The flange 30 does not function as the thread on a screw

45 being driven into wood, but rather the flange serves a purpose similar to the high pitch flange on the sides of a wood auger bit, i. e., the flange conveys upwardly the gravel displaced by the penetrating action of the screen. After the

50 screen 26 has reached the proper depth or substantially the bottom of the cavity 14, any suitable form of packer 32 may be placed so as to fill the space between the casing 18 and the pipe 24 above the gravel which has been moved upwardly within the casing, and the well may

then be placed on production. If desired, in order to protect the outer surface of the screen from abrasion by the gravel 22, the screen may be covered prior to placing it in the hole by a coating or sheath of decomposable material such as an acid soluble resin or metal. In such a case after the screen is in place the decomposable sheaths may be destroyed by introducing into the screen through the pipe string a suitable chemical, such as an acid, as is well known.

Figure 2 illustrates an embodiment wherein an inner tubular member 34 attached to the lower end of a pipe string 24 serves both to cut the hole and to remove the gravel. The tube 34 has at its lower end a cutting edge 36 to facilitate movement through the gravel bed 22. Disposed about the inner tube 34 is an outer tube or sleeve 38 preferably formed of a decomposable substance such as an acid soluble resin or metal. The tube 38 may also contain perforations, not shown, in which case it may be of permanent construction. The inner tube 34 is preferably connected to the lower end of the pipe 24 by means of a relatively low pitch right hand thread 40 and the upper end of the tube 34 is upset slightly so as to provide material for a coarse or high pitch right hand thread 42. The lower end of the tube 34 is provided with a valve 44 of any suitable type adapted to close when the tube 34 filled with gravel is raised.

In accordance with this embodiment the tubular members 34 and 38 are lowered and rotated so that they will be forced through the gravel bed 22. In some cases a reciprocatory vertical movement may be found more satisfactory in forcing the tubes through the gravel bed. Preferably the cavity 14 is provided at its bottom with a hole extension 46 of substantially the same diameter as the tube 38. When in the position shown in Figure 2 the inner tube 34 will be filled with gravel and by rotating the pipe string 34 in a left hand direction the connection 42 will become unthreaded whereupon, when the pipe string 24 is pulled upwardly the valve 44 will close, thus trapping the gravel within the tube 34 in which it can be then pulled upwardly to the surface. The hole in the gravel will then be maintained by the outer tube 38 into which a screen, not shown, can then be lowered on a production tubing string. The tube 38 can then be destroyed as by means of an acid as explained with reference to Figure 1. When the tube 38 contains perforations, it may be left in the well to form a permanent protection for the screen. By placing a packer similar to that shown at 32 in Figure 1 between the pipe 24 and the casing 18 the well will be ready for production. Due to the provision of the hole extension 46, gravel from the bed 22 will be prevented from entering the tube 38 at its lower end.

In Figure 3 is shown an embodiment somewhat similar to that of Figure 2 but in which the outer tube member 50 consists of a screen or perforated liner. Within the screen 50 is an inner tube 52 having a suitable valve 54 at its lower end, this valve being similar to the valve 44 of Figure 2. The inner tube 52 rests upon a shoulder 56 at the bottom of the screen 50 and the lower end of the screen is preferably provided with a suitable cutting edge 58 to facilitate its passage through the gravel bed. The lower end of the pipe string 24 is provided with a double bell-shaped portion 60 having an upper, relatively fine, right hand thread 62 to which the inner tube 52 is attached and a lower, relatively coarse, right hand thread 64

to which the screen 50 is attached. While being lowered through the gravel bed 22 the inner tube 52 fills with gravel and after reaching a desired depth preferably such that the lower end of the screen 52 will be within the hole extension 46, a few left hand turns of the pipe string 24 will disconnect the screen 50 at the threaded joint 64, after which an upward pull on the pipe string will cause the valve 54 to close to trap the gravel within the tube 52 and that tube with its gravel can then be pulled upwardly to the surface. A flow tubing can then be lowered and screwed onto the upper end of the screen 50 and after placing a packer similar to that shown in 24 in Figure 1 the well will be in condition for production.

In the embodiment illustrated in Figure 3 the screen 50 can, if desired, be provided with an outer sheath of a decomposable material in order to protect the screen from abrasion, this sheath being subsequently removed as described with reference to Figure 1.

Figure 4 shows an alternative form of connection between the pipe string 24 and the tube 52 and the screen 50. In this form the upper end of the inner tube 52 has affixed thereto a collar 66 and the lower end of the pipe string has a bell-shaped portion 68 provided at its lower end with threads 70 adapted to engage threads on the upper end of the screen 50. Within the lower portion of the bell 68 is a thickened annular portion 72 into which is threaded a collar 74. In assembling, the tube 52 with its collar 66 attached is placed within the bell 68 after which the collar 74 is screwed in place. The screen 52 is then screwed to the lower end of the bell. With this form when it is desired to move the inner tube 52 with its gravel from the hole the pipe string 24 is rotated to disconnect the threaded joint 70 and upward movement of the pipe 24 will then cause the collar 74 to engage the collar 66 so as to pull the tube 52 upwardly.

In Figure 5 is shown another slight modification in which the screen 50 is also provided with a valve 76, the shoulder 56 being disposed above the valve. In this case a slight upward pull on the pipe string 24 prior to disengaging the threads 64 of Figure 3 or the threads 70 of Figure 4, will raise the screen 50 so that gravel trapped within its lower end will cause the valve 76 to close in which position it will be held by a latch 78. With this form it would not be necessary to place the lower end of the screen in a hole projection such as is indicated at 46 in Figure 3.

Obviously many modifications and variations of the invention as hereinbefore set forth may be made without departing from the spirit and the scope thereof but only such limitations should be imposed as are indicated in the appended claims.

I claim:

60 1. A method of completing a well with a gravel packed screen which comprises substantially filling the lower portion of the well with gravel, forcing a pair of open-bottomed concentric tubes through the gravel filling coaxially with the well bore and removing the inner tube with the gravel contained therein while leaving the outer tube within the gravel filling.

65 2. A method of completing a well with a gravel packed screen which comprises substantially filling the lower portion of the well with gravel, forcing a pair of open-bottomed concentric tubes through the gravel filling coaxially with the well bore, removing the inner tube with the gravel contained therein while leaving the outer tube within the gravel filling, replacing said inner

tube with a well screen, and then destroying said outer tube.

3. A bottom-hole assembly for a well bore having a mass of gravel in its lower portion comprising an outer and an inner tube disposed concentrically and attached to the lower end of a string of pipe, the lower ends of said tubes being normally open, and the outer tube being attached to the pipe string by means of a releasable connection, means for forcing said tubes downwardly into the gravel mass, a check valve in the lower end of said inner tube adapted to close on upward movement of said inner tube, and means for actuating said releasable connection to disconnect said outer tube from said pipe string so that said inner tube can be pulled upwardly to the surface.

4. A bottom-hole assembly for a well bore having a mass of gravel in its lower portion comprising a tube attached to the lower end of a string of pipe, a well screen disposed concentrically around said tube and also attached to said string of pipe, the lower ends of said tube and screen being normally open, means for forcing said tube and screen downwardly into

25

the gravel mass, a check valve in the lower end of said tube adapted to close on upward movement of said tube, and means for disconnecting said screen from said pipe string and pulling said tube upwardly to the surface.

5. A bottom-hole assembly for a well bore having a mass of gravel in its lower portion comprising an outer and an inner tube disposed concentrically and attached to the lower end of a string of pipe, the lower ends of said tubes being normally open, and the outer tube being attached to the pipe string by means of a releasable connection, means for forcing said tubes downwardly into the gravel mass, a check valve in the lower end of said inner tube adapted to close on upward movement of said inner tube, means for disconnecting said outer tube from said pipe string at said releasable connection and pulling said inner tube upwardly to the surface, means for replacing the inner tube with a well screen and means for subsequently destroying said outer tube.
